Fig.3

Fig.5

Fig. 8

Fig. 10

Fig. 7

Fig. 9

FIGURES 1 and 2 are front perspectives of a shower enclosure embodying the new design with the folding door of the enclosure shown closed and open, respectively;

FIG. 3 is a side elevation of the shower enclosure as shown in FIG. 1;

FIG. 4 is a top plan of the enclosure as shown in FIGS. 1 and 3;

FIG. 5 is a side elevation of the enclosure as shown in FIG. 2;

FIG. 6 is a top plan of the enclosure as shown in FIGS. 2 and 5;

FIG. 7 is a side elevation of a modified form thereof with the folding door of the enclosure shown closed;

FIG. 8 is a top plan of the enclosure as shown in FIG. 7;

FIG. 9 is an elevation of another side of the FIG. 7 enclosure with the folding door shown open; and

FIG. 10 is a top plan, rotated 90°, of the enclosure as shown in FIG. 9.

This application is a continuation of my applications Serial No. D.84,663, filed April 7, 1965, and Serial No. D.85,388, filed May 20, 1965, both now abandoned.

I claim:

The ornamental design for a shower enclosure, substantially as shown and described.

No references cited.
